UNITED STATES PATENT OFFICE.

WILLIAM A. LORENZ, OF HARTFORD, CONNECTICUT.

DESIGN FOR A CAN, JAR, OR SIMILAR ARTICLE.

44,930.

Specification for Design.

Patented Nov. 25, 1913.

Application filed February 11, 1911. Serial No. 608,132. Term of patent 14 years.

To all whom it may concern:

Be it known that I, WILLIAM A. LORENZ, a citizen of the United States, residing at Hartford, in the county of Hartford and State of Connecticut, have invented a new, original, and ornamental Design for Cans, Jars, or Similar Articles, of which the following is a specification, reference being had to the accompanying drawing, forming part thereof.

The figure is a side elevation of a can or jar showing my new design.

I claim:

The ornamental design for a can, jar, or similar article, as shown.

WILLIAM A. LORENZ.

Witnesses:

K. E. PEILER,
NELLIE PHOENIX.
